CLAIM

The ornamental design for an angle broom shroud, as shown and described.

DESCRIPTION

FIG. 1 is a front perspective view of an angle broom shroud showing my new design.

FIG. 2 is a top plan view thereof.

FIG. 3 is a bottom plan view thereof.

FIG. 4 is a side elevational view as seen from the left of FIG. 2.

FIG. 5 is a right side elevational view thereof.

FIG. 6 is a rear elevational view thereof.

The broken lines showing of a handle and broom bristles in FIG. 1 and a handle in FIG. 6 are for illustrative purposes only and form no part of the claimed design.

FIG. 1

FIG. 2

FIG. 3

FIG. 4

FIG. 5

FIG. 6
